The ornamental design for an light emitting diode, as shown and described.

DESCRIPTION

FIG. 1 is a front bottom perspective view of an LED showing our design;

FIG. 2 is a bottom view thereof;

FIG. 3 is a back view thereof;

FIG. 4 is a top view thereof;

FIG. 5 is a front view thereof;

FIG. 6 is side view thereof;

FIG. 7 is an opposing side view thereof; and,

FIGS. 8-11 are alternate front views of our LED design, with the other views corresponding to FIGS. 1-4, 6 and 7.

The broken lines shown herein are for illustrative purposes only and form no part of the claimed design.
